A. H. JONES

CUSHION

Filed May 28, 1925

A. H. Jones
By Watson E. Coleman
Attorney

UNITED STATES PATENT OFFICE.

ALEXANDER HENRY JONES, OF KANSAS CITY, KANSAS.

CUSHION.

Application filed May 28, 1925. Serial No. 33,527.

To all whom it may concern:

Be it known that I, ALEXANDER H. JONES, a citizen of the United States, residing at Kansas City, in the county of Wyandotte 5 and State of Kansas, have invented certain new and useful Improvements in Cushions, of which the following is a specification, reference being had to the accompanying drawings.

- 10 This invention relates to certain improvements in cushions and has relation more particularly to a device of this general character especially designed and adapted for use in connection with auto seats, and it is 15 an object of the invention to provide a cushion of this kind constructed in a manner whereby the front and back may be relatively adjusted in accordance with the requirements of practice.
- 20 Another object of the invention is to provide a cushion of this character particularly adapted to provide a support for the back of the occupant of the seat and more particularly the driver of an automobile.
- 25 The invention consists in the details of construction and in the combination and arrangement of the several parts of my improved cushion whereby certain important advantages are attained and the device 30 rendered simpler, less expensive and otherwise more convenient and advantageous for use, as will be hereinafter more fully set forth.

The novel features of my invention will 35 hereinafter be definitely claimed.

In order that my invention may be the better understood, I will now proceed to describe the same with reference to the accompanying drawings, wherein:

- 40 Figure 1 is a vertical sectional view taken through a cushion constructed in accordance with an embodiment of my invention;

Figure 2 is a sectional view taken substantially on the line 2—2 of Figure 1;

- 45 Figure 3 is a detailed sectional view taken substantially on the line 3—3 of Figure 1.

As disclosed in the accompanying drawings, 1 denotes a back board of requisite dimensions and 2 denotes a front board, said 50 front board having a suitable padding 3 disposed over the outer face thereof. Interposed between the boards 1 and 2 adjacent the corners thereof are the expandible springs 4 of requisite tension, the relative 55 separating movement of the boards 1 and 2 under the influence of the members or

springs 4 being limited by the straps 5 secured to said boards and to the side members 6 of a frame F.

The frame F is positioned substantially 60 midway between the boards 1 and 2 and is free therefrom, said frame F being rectangular in form and having the lower portion of its side members 6 connected by a cross member 7, the central portion of the member 7 being provided with a bearing or sleeve 8 through which is freely disposed a rod 9. The inner end portion of the rod 9 has swivel engagement therewith a member provided with the oppositely directed ears 10 to which 65 are pivotally connected the links 11, said links being also pivotally connected, as at 12, to the front and back boards 1 and 2. By requisite endwise movement of the rod 9 the links 11 operate to move the boards 1 70 and 2 one with respect to the other, an innermost adjustment of said boards 1 and 2 being indicated by broken lines in Figure 1.

An end member 14 of the frame F at its 75 central part is provided with an inwardly extending housing 15 through which the outer end portion of the rod 9 is threaded the extremity of the rod 9 within the housing 15 being provided with an operating member 16. The member 16 provides means 80 whereby the rod 9 may be rotated as desired to either extend or retract the boards 1 and 2 one with respect to the other.

The covering 17 for the pad 3 has its 85 marginal portion extended and suitably secured to the edges of the back board 1 whereby the parts between the boards 1 and 2 are completely housed and protected.

From the foregoing description it is 90 thought to be obvious that a cushion constructed in accordance with my invention is particularly well adapted for use by reason of the convenience and facility with which it may be assembled and operated, and it will also be obvious that my invention 95 is susceptible of some change and modification without departing from the principles and spirit thereof and for this reason I do not wish to be understood as limiting myself to the precise arrangement 100 and formation of the several parts herein shown in carrying out my invention in practice except as hereinafter claimed.

I claim:

1. A cushion comprising, in combination, 110 front and back boards, an expandible medium interposed therebetween, a frame

positioned between the boards, a cross member carried by the frame, a rod freely disposed through said cross member and inwardly of the frame, links pivotally connected with the boards, a member in swiveled connection with the inner portion of the rod, said links being also pivotally connected with said member, said rod being in threaded engagement with a member of the frame.

2. A cushion comprising, in combination, front and back boards, an expandible medium interposed therebetween, a frame

positioned between the boards, a cross member carried by the frame, a rod freely disposed through said cross member, links operatively connecting an end portion of the rod and the boards, a housing carried by a member of the frame, said rod being threaded through a wall of the housing, and means carried by the portion of the rod within the housing for rotating the rod.

In testimony whereof I hereunto affix my signature.

ALEXANDER HENRY JONES.
